[57] CLAIM

The ornamental design for a bench, as shown and described.

DESCRIPTION

FIG. 1 is a perspective view of our new design for a bench as seen from a point above and to one side of the design, with the other side corresponding;

FIG. 2 is a plan view of the top of the bench;

FIG. 3 is a perspective view of our new design for a bench as seen from a point above and from the front of the bench; and,

FIG. 4 is a rear view of the bench.

The partial depiction of black shading which indicates the color black in the drawings is understood to be continuous throughout.
